UNITED STATES PATENT OFFICE.

LOUIS J. SOMMER, JR., OF PHILADELPHIA, PENNSYLVANIA.

VALVE.

SPECIFICATION forming part of Letters Patent No. 794,053, dated July 4, 1905.

Application filed January 18, 1904. Serial No. 189,418.

To all whom it may concern:

Be it known that I, LOUIS J. SOMMER, Jr., a citizen of the United States, residing at Philadelphia, in the county of Philadelphia and State of Pennsylvania, have invented a new and useful Improvement in Valves, of which the following is a specification.

My invention relates to cocks or valves.

It consists of a novel construction of a waste 10 by which liquid is permitted to pass from the outlet end of the cock when the same is closed.

It further consists of means for preventing waste at such outlet when the cock is partially or fully open.

15 It further consists of means for providing a waterway of relatively large size and capable of withstanding a high pressure.

It further consists of other novel features of construction, all as will be hereinafter fully 20 set forth.

Although all or some of the features of my invention may be applied to different sorts of cocks or valves and although it is obvious that all of the features of the invention need 25 not be used in the same construction, I have shown as the embodiment of my invention a stop and waste cock, which is represented in the drawing partly in vertical section and partly in elevation, and in which 1 designates a body

30 having inlet and outlet ends 2 and 3, respectively, and a chamber 4, surmounted by a bonnet 5, in which is a vertical cylindric portion 6, having a shoulder 7 at its upper end. The bonnet 5 is interiorly and exteriorly

35 threaded to receive a correspondingly-threaded nut 8 and a cap 9. Within the body 1 of the cock is an angularly-disposed seat 10, adjacent which at its lower end is a lug 11, having a substantially vertical face 12. On the

40 seat 10 rests a washer 13, secured to a valve-plate 14. The plate 14 may be integral with or secured to a hollow stem or sleeve 15 and may have a brace 16 connecting the sleeve and valve. At the upper end of the sleeve

45 15 is a shoulder 17, on which is seated a cup-shaped washer 18, the exterior diameter of which corresponds to the interior diameter of the cylindric portion 6. A spindle 19 has at its upper end the usual handle 20 and is pro-

vided with an offset 21, engaged between the 50 lower end of the threaded nut 8 and an annular projection 22 near the upper end of the bonnet 5. The lower end of the spindle 19 is threaded at 23 to engage in the threaded sleeve 15. Extending vertically through the spindle 19 is a bore 24, having a lateral opening 25 near the lower end of the threaded portion 23. I have also shown a lateral opening 26 through the wall of the chamber 6.

The operation of my device will be readily 60 understood from an inspection of the drawing. It will be seen that when the valve is closed, as shown, the washer 13 is firmly held between the valve-seat 10 and the valve-plate 14. It will also be seen that any pressure of 65 water from the inlet end 2 of the cock bearing against the plate 14 will cause the lower side of the plate to press against the vertical portion 12 of the lug 11, which lug will thus serve to take the strain and prevent the plate 70 from being lifted from its seat. As the lateral opening 25 of the spindle 19 is now open, it is evident that any liquid contained in a pipe or vessel connected with the outlet end 3 of the cock will be permitted to waste 75 through the bore 24 of the spindle or lateral aperture 26 in the upper portion of the bonnet 5. It is evident that either one of these openings—that is, the bore 24 or the lateral aperture 26—may be dispensed with. I have 80 shown both to indicate that the use of either is in accordance with my invention. When the cock or gate is opened by raising the valve 14 from its seat and into the chamber 4, it is evident that the entire waterway will be clear, 85 so that practically no resistance is offered to the passage of liquid therethrough. It is also evident that the aperture 25 will be engaged within the sleeve 15 and that the cup-washer 18 will speedily enter and fill the chamber 6 90 in the upper portion of the bonnet 5, so that almost as soon as the valve begins to open the waste will be cut off. When the valve is fully open, it is evident that the upper part of the cup-washer 18 will seat against the shoulder 7 95 at the upper end of the chamber 6. At the same time the annular shoulder 27 will bear against the shoulder at the lower end of the

chamber 6, thereby absolutely preventing loss of liquid through either or both of the waste-exits 24 and 26.

The advantages of my device are the open waterway produced by the raising of the valve 14 into the chamber 4, the large chamber in the cock in which the valve is received when the cock is open, the provision for cutting off the waste as soon as the cock begins to open, and for absolutely cutting it off when the cock is fully opened.

It is evident that various changes may be made by those skilled in the art which will come within the scope of my invention, and I do not, therefore, desire to be limited in every instance to the exact construction herein shown and described.

Having thus described my invention, what I claim as new, and desire to secure by Letters Patent, is—

In a cock or valve, a body having a substantially straight passage therefor, providing a waterway, a bonnet removably secured to said body, a chamber of reduced size in said bonnet above said body, said chamber having

a waste-opening, a valve movable transversely of said waterway and adapted to control the same, a spindle for said valve and means for operating the same to raise and lower said valve, a cup-washer mounted upon said stem and movable therewith and bodily removed from said chamber to provide a free passage to the waste-opening when the valve is closed and adapted to fill said chamber when the valve is raised from its seat, whereby said valve-opening is immediately closed and said cup-washer being adapted to closely fit said chamber and to be forced against the sides thereof by the force of the water and a shoulder or second valve movable with said spindle, said second valve being adapted to bear against the shoulder or wall at the lower end of the chamber forming a positive closure, and preventing any pressure from reaching the cup-valve.
